(57) **CLAIM**

The ornamental design for a charging stand for smart speaker, as shown and described.

DESCRIPTION

FIG. 1 is a perspective view of a charging stand for smart-speaker showing our new design;

FIG. 2 is another perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The dashed broken lines illustrate portions of the charging stand for smart speaker that form no part of the claimed design. The oblique line shading shown in the drawings indicates a transparent or translucent surface.

1 Claim, 6 Drawing Sheets
